ABSTRACT

A front support mechanism for safety ski bindings which includes a support structure and lateral support arms at the support structure which are pivotal laterally against a resilient detent effect about pivot axes disposed perpendicularly or approximately perpendicularly to the ski surface; the pivot axes of the lateral support arms are thereby displaced in dependence on the pivot movement by a rolling-off action of the support arms at a roll-off part which is, for example, fixed to the ski.

FRONT SUPPORT MECHANISM FOR SAFETY SKI BINDING

The present invention relates to a front support mechanism for safety ski bindings having a support member and lateral support arms which are pivotal laterally against a resilient detent effect at the support member about pivot axes perpendicular or approximately perpendicular to the ski surface.

The present invention is now concerned with the task to enable such a guidance of the lateral support arms with means which are as simple and frictionless as possible that the support arms carry out a pivot movement whose pivot radius changes with the stroke or deflection movement of the support arms.

Accordingly, the present invention essentially consists in that the pivot axes of the lateral support arms are displaced in dependence on the pivot movement by a rolling off action of the support arm at a roll-off part, for example, fixed at the ski. Preferably, the displacement takes place in such a manner that the pivot axes are displaced rearwardly in the course of the outward pivot stroke of the support arms and/or that the pivot radii are reduced.

It can be achieved by the present invention that the lateral support arms, for example, in case of a twisting fall, move initially essentially laterally and only after a certain stroke carry out a stronger movement in the forward direction by the displacement of the pivot axis, particularly in such a manner that with small lateral movements of the front portion of the boot, a release thereof is not yet achieved but instead the boot returns again into the center position after the cessation of the laterally directed force and is released by the lateral support arms only with stronger lateral strokes.

The displacement of the pivot axis can take place continuously or stepwise. In a particularly simple embodiment the support arms and the roll-off part fixed with the ski are in engagement with one another by a toothed connection. In the simplest construction, the toothed arrangement may include two teeth mutually offset in the longitudinal direction of the ski, especially in such a manner that at first the forward tooth, as viewed in the longitudinal direction of the ski, and after a certain pivot stroke the rear tooth forms the pivot axis of the lateral support arm.

In a structurally particularly advantageous embodiment, the two lateral support arms are supported so as to roll off along an outer wall of the support member from the inside thereof. For purposes of securing the lateral support arms against lifting off from the part which is in roll-off contact with the same, the lateral support arms may be additionally guided, for example, by means of pins or the like in or along arcuately shaped guide surfaces. The guidance in these additional guide means can take place with only slight frictional resistance because during the pivoting of the lateral support arms the lateral pressure force is absorbed at the roll-off points of the lateral support arms.

In a spatially compact construction, a coil or helical spring serving as detent spring is provided on a pin arranged between the lateral support arms, which pin is carried by a fork guided longitudinally adjustable in slots of the support member for purposes of adjusting the spring stress. The support arms are thereby supported against the spread apart ends of the spring

which are additionally stressed during the lateral pivoting movements of the support arms.

These and further objects, features and advantages of the present invention will become more apparent from the following description when taken in connection with the accompanying drawing which shows, for purposes of illustration only, two embodiments in accordance with the present invention, and wherein:

10 FIG. 1 is a plan view on safety ski binding front support mechanism according to the present invention in cross section taken along 1-1 of FIG. 2;

FIG. 2 is a cross-sectional view along line 2-2 of FIG. 1;

15 FIG. 3 is a cross-sectional view along line 3-3 of FIG. 1;

FIG. 4 is a side elevational view of the front mechanism of a safety ski binding in accordance with the present invention;

20 FIG. 5 is a partial view on the support mechanism of FIG. 2;

FIG. 6 is a partial plan view on the support mechanism corresponding to FIG. 1, however, with a laterally deflected support arm;

25 FIG. 7 is a plan view, similar to FIG. 1, on another embodiment of a support mechanism for a safety ski binding in accordance with the present invention; and

FIG. 8 is a cross-sectional view, similar to FIG. 3, and taken along line 8-8 of FIG. 7.

Referring now to the drawing wherein like reference numerals are used throughout the various views to designate like parts, reference numeral 10 designates a ski on which is secured in any suitable manner, for example, by means of screws 11, a support structure generally designated by reference numeral 12 which is thus 30 fixedly arranged with respect to the ski. This support member 12 is constructed housing-shaped and includes a base plate 13, a cover plate 14, lateral walls 15, a forward end wall 16 and a rear center web 17 connecting the base plate 13 with the cover plate 14, whereby the center web 17 is delimited on its two sides by two apertures 18.

Corresponding to FIG. 3, guide pins 19 which extend perpendicular to the ski surface are riveted into the base plate 13 and into the cover plate 14; the lateral 45 support arms generally designated by reference numerals 20 and 21 are in engagement with the guide pins 19 by means of curved slots 22. The support arms 20 and 21 are each constituted by two plate-shaped parts, and more particularly by a lower plate 20a and 21a and by an upper plate 20b and 21b, respectively, which are connected into a unitary structure by upright walls 23. Bearing members 24 are inserted between the plates 20a, 20b and 21a, 21b; the boot sole holders 25 engaging over the boot sole 27, are supported adjustably in height at the bearing members 24 by means of threaded screws or bolts 26.

For the further support of the forward edge of the boot sole 27, indicated in FIG. 1 in dash and dot lines, an adjusting screw 28 is threadably arranged in the center web 17 of the support structure 12.

The lateral walls 15 of the support member 12 serve as roll-off parts for the lateral support arms 20 and 21. To that end, they are provided each with two pairs of slot-like apertures 29 and 30, into which engage or may engage projections or teeth 31 and 32 rounded off in circular shape and provided at the plates 20a, 20b and 21a, 21b, when the lateral support arms 20 and 21 are

pivoted outwardly. Teeth 31 and 32 are thereby arranged at an arcuately shaped edge 33 which delimit the aforementioned plates approximately in a circular arc about a center point of curvature 19a (FIG. 1a) which coincides approximately with the axis of the guide pin 19 when the latter is disposed corresponding to FIG. 1 at the inner end of the arcuate guide slot 22.

Furthermore, abutment pins 34 and 35 are fixedly arranged at the lateral support arms 20 and 21 which cooperate with a detent spring generally designated by reference numeral 36 and constructed as coil or helical spring. The spring 36 is wound about a pin 37 which is retained by a fork 38 and is provided at its upper and at its lower end with flattened off portions 39 between the lateral support arms 20 and 21 or the plates thereof so that wedge- or web-like projections 40 and 41 are formed which engage into the slots 42 and 43 in the base plate 13 and in the cover plate 14, respectively, and are guided therein. For purposes of adjusting the pin 37 or the detent spring 36 in the ski longitudinal direction x_1, x_2 , the fork 38 includes a forwardly directed threaded bolt 44 whose thread is in engagement with a nut 45 which, in its turn, is rotatably but non-displaceably supported in the front end wall 16 of the housing-like support member 12. The upper slot 43 may be provided with a scale 43a (FIG. 5) in order to indicate the adjusted spring stress in conjunction with a pointer 41a at the upper projection 41.

The two ends 46 and 47 of the spring 36 are spread apart toward the rear, crossing one another in such a manner that they abut at the abutment pins 34 and 35 fixedly arranged at the lateral support jaws 20 and 21 from the outside thereof. The spring ends are preferably provided with curved portions 48 and 49 in order to influence the disengagement of the lateral support arms 20 and 21 in the manner to be described more fully hereinafter.

In the position according to FIG. 1, the lateral support arms 20 and 21 are in their center rest position and by means of the teeth 31 are in engagement with the apertures 29 in the lateral walls 15 of the support member 12.

If, for example, as a result of a twisting fall, a force P (FIG. 1) occurs, which seeks to pivot laterally the boot and therewith the lateral support arm 20, then the support arm 20 supports itself in the point A by means of the tooth 31 at the lateral wall 15 of the support member 12 which serves as roll-off part. The support arm 20 is thereby guided by means of the arcuately shaped slot 22 on the guide pin 19 fixedly arranged in the support structure 12. As a result thereof the abutment pin 34 moves along a circular arc about the point A in the direction of arrow y, which by reason of the simultaneous support of the other spring end 47 at the abutment pin 35 is possibly only by deformation of the bent-out end 46 of the spring. Depending on the adjustment of the spring stress by displacement of the fork 38 in the direction of arrow x_1, x_2 , a controllable detent resistance is exerted by the detent spring 36 against the pivoting of the support arm 20 in the direction of arrow y. By a corresponding selection of the bent portion 48 (or 49 during the deflection of the support arm 21) the characteristics for the detent resistance can be further varied, for example, in such a manner that at first the detent resistance increases up to a maximum resistance and after a certain pivot stroke of the support arm is again decreased.

In a predetermined pivot position, approximately corresponding to FIG. 6, the tooth 32 engages into the aperture 30 whereby the lateral support arm 20 is now supported in the point B at the tooth 32. The abutment pin 34 has preferably already exceeded in this case the maximum bent-out portion of the spring end 46 at the place 48 and can now move outwardly in the direction of arrow y, against a reduced spring resistance and with a reduced radius of curvature of its movement. The support arm 20 carries out a corresponding pivot movement in that it moves rapidly away from the boot in the forward direction and thereby releases the boot. The maximum pivot stroke is limited, for example, by the end wall 22a (FIG. 1) of the curved guide slot 22.

A somewhat different embodiment is illustrated in FIG. 7 and 8. It differs from the described embodiment essentially only in that the guide surface and guide pin for the lateral support arms are arranged in kinematic reversal. The guide pins 119 are, in this case, connected securely with the lateral support arms 20 and 21 whereas in lieu of the arcuately shaped guide slots 22, inner walls 122 are arranged at the support member 15 along which the guide pins may slide.

For limiting the pivot stroke, the wall 122 terminates in a cross wall 122a against which the pin 119 abuts in the end position 119'. As to the rest, the operation of the mechanism according to FIGS. 7 and 8 is the same as in the case of the embodiment of FIG. 1 to 6.

While I have shown and described two embodiments in accordance with the present invention, it is understood that the same is not limited thereto but is susceptible of numerous changes and modifications as known to those skilled in the art, and I therefore do not wish to be limited to the details shown and described herein but intend to cover all such changes and modifications as are encompassed by the scope of the appended claims.

What I claim is:

1. A ski boot support mechanism for safety ski bindings comprising:
a support structure attachable to a ski surface,
at least one boot sole holding means,
lateral support arm means attached to and movable
with each of said boot sole holding means,
pivot support means for supporting each of said lateral support arm means at said support structure
for pivotal movement about a support arm pivot
axis which extends at least approximately perpendicular to said ski surface,
and resilient means for resiliently resisting pivotal
movement of said lateral support means,
said pivot support means including roll-off means for
accommodating predetermined movement of each
of said support arm pivot axes during pivotal move-
ment of said lateral support arm means,
characterized in that said pivot support means in-
cludes means for assuring that each of the pivot
axes are displaced rearwardly in the course of the
outward pivoting stroke of the support arm means.
2. A support mechanism according to claim 1,
wherein said support mechanism is a front support
mechanism with said boot sole holding means including
toe hold-down means, characterized in that said pivot
support means includes means for assuring that the
radii of curvature of the pivot movements decrease in
the course of the outward pivot stroke of the support
arm means.

3. A ski boot support mechanism for safety ski bindings comprising:

a support structure attachable to a ski surface,
at least one boot sole holding means,
lateral support arm means attached to and movable
with each of said boot sole holding means,
pivot support means for supporting each of said lateral support arm means at said support structure
for pivotal movement about a support arm pivot
axis which extends at least approximately perpendicular to said ski surface,
and resilient means for resiliently resisting pivotal
movement of said lateral support arm means,
said pivot support means including roll-off means for
accommodating predetermined movement of each
of said support arm pivot axes during pivotal move-
ment of said lateral support arm means,
characterized in that pivot support means includes
means for assuring that the radii of curvature of the
pivot movements decrease in the course of the out-
ward pivot stroke of the support arm means.

4. A support mechanism according to claim 3,
wherein said support mechanism is a front support
mechanism with said boot sole holding means including
toe hold-down means, characterized in that the support
arm means and roll-off means are in engagement with
each other by toothed means.

5. A front support mechanism according to claim 4,
characterized in that the toothed means include two
teeth mutually offset in the ski longitudinal direction.

6. A front support mechanism according to claim 5,
characterized in that the lateral support arm means in-
clude said teeth, by means of which they engage in ap-
erture means provided in the support structure.

7. A front support mechanism according to claim 6,
characterized in that the teeth are rounded-off approxi-
mately circularly shaped.

8. A front support mechanism according to claim 6,
characterized in that the lateral support arm means
support themselves rolling-off at an outer wall of the
support structure serving as roll-off means from the in-
side thereof.

9. A front support mechanism according to claim 8,
characterized in that the lateral support arm means are
guided against lifting off from the roll-off means in roll-
off contact with the lateral support arm means.

10. A front support mechanism according to claim 9,
characterized in that pin means guided along arcuately
shaped surface means are provided for the guidance of
the lateral support arm means.

11. A front support mechanism according to claim
10, characterized in that said pin means are guided in
arcuately shaped guide slot means.

12. A front support mechanism according to claim
10, characterized in that said means are guided on ar-
cuately shaped guide surface means.

13. A front support mechanism according to claim
10, characterized in that the guide surface means are
arranged in the lateral support arm means and the pin
means at the structural part.

14. A front support mechanism according to claim 9,
characterized in that for purposes of guidance the pin
means are arranged at the lateral support arm means
and the guide surface means as inner walls at the sup-
port structure.

15. A front support mechanism according to claim
14, characterized in that the guide pin means are ar-

ranged in the center point of curvature of the toothed
means rolling-off at the support structure in the rest
condition of the lateral support arm means.

16. A front support mechanism according to claim 9,
characterized in that guide pin means are arranged in
the center point of curvature of the toothed means rolling-
off at the support structure in the rest condition of
the lateral support arm means.

17. A front support mechanism according to claim 9,
characterized in that the lateral support arm means in-
clude two plate-shaped members arranged one above
the other at a distance which are connected with each
other by at least one of the two parts consisting of wall
means and guide pin means and which carry the
toothed means enabling the roll-off movement of the
support arm means.

18. A front support mechanism according to claim
17, characterized in that the two plate shaped members
are connected with each other by said wall means and
by said guide pin means for the support arm means.

19. A front support mechanism according to claim
17, characterized in that the roll-off movement of the
lateral support arm means is limited by abutment
means.

20. A front support mechanism according to claim
19, characterized in that abutment means are arranged
at the ends of the guide surface means.

21. A front support mechanism according to claim
20, characterized in that the abutment means are formed
by transversely extending wall parts delimiting
the guide surface means.

22. A front support mechanism according to claim
20, characterized in that a spring means is provided for
carrying out the resilient detent effect, said spring
means having ends which are spread apart on both
sides and so abut against abutment members provided
at the lateral support arm means that during a lateral
pivoting of the support arm means the spring means is
40 additionally stressed.

23. A front support mechanism according to claim
22, characterized in that the spring means is a coil
spring.

24. A front support mechanism according to claim
22, characterized in that the spring means is a spiral
spring.

25. A front support mechanism according to claim
22, characterized in that the ends of the spring means
are bent out in relation to the pivot axes of the respec-
tively associated lateral support arm means in such a
manner that with a lateral pivoting of the support arm
means the spring means is at first additionally stressed
and thereafter is again unstressed.

26. A front support mechanism according to claim
25, characterized in that the spring means is arranged
on an adjustable pin adjustable in the ski longitudinal
direction and disposed essentially perpendicularly to
the ski surface.

27. A front support mechanism according to claim
26, characterized in that the axis of the pin carrying the
spring means extends between the lateral support arm
means and in that said pin is flattened off on both sides
thereof between the lateral support arm means.

28. A front support mechanism according to claim
27, characterized in that the pin is flattened off on both
sides between the plate shaped members forming the
support arm means.

29. A front support mechanism according to claim 27, characterized in that the pin is supported in a fork guided within slots of the support structure, said fork being longitudinally adjustably mounted.

30. A front support mechanism according to claim 29, characterized in that said fork is longitudinally adjustably arranged in an end wall of the support structure.

31. A front support mechanism according to claim 29, characterized in that the adjustable pin is constructed as indicating element for the spring tension.

32. A front support mechanism according to claim 31, characterized in that a flattened off end of the pin is constructed as indicating element for the spring tension.

33. A front support mechanism according to claim 29, characterized in that in addition to the lateral support arm means, a central adjustable abutment means is provided for the support of the front portion of a ski boot.

34. A front support mechanism according to claim 33, characterized in that the lateral support arm means project through apertures of the housing-shaped support structure and in that a threaded member arranged in a center web between the aperture means is provided as center adjustable abutment means for the front portion of the ski boot.

35. A ski boot support mechanism for safety ski bindings comprising:

a support structure attachable to a ski surface,
at least one boot sole holding means,
lateral support arm means attached to and movable
with each of said boot sole holding means,
pivot support means for supporting each of said lateral support arm means at said support structure
for pivotal movement about a support arm pivot axis which extends at least approximately perpendicular to said ski surface,
and resilient means for resiliently resisting pivotal movement of said lateral support arm means,
said pivot support means including roll-off means for accommodating predetermined movement of each of said support arm pivot axes during pivotal movement of said lateral support arm means,

characterized in that the support arm means and roll-off means are in engagement with each other by toothed means.

36. A support mechanism according to claim 35, wherein said support mechanism is a front support mechanism with said boot sole holding means including toe hold-down means, characterized in that the toothed means include two teeth mutually offset in the ski longitudinal direction.

37. A ski boot support mechanism for safety ski bindings comprising:

a support structure attachable to a ski surface,
at least one boot sole holding means,
lateral support arm means attached to and movable
with each of said boot sole holding means,
pivot support means for supporting each of said lateral support arm means at said support structure
for pivotal movement about a support arm pivot axis which extends at least approximately perpendicular to said ski surface,
and resilient means for resiliently resisting pivotal movement of said lateral support arm means,

said pivot support means including roll-off means for accommodating predetermined movement of each of said support arm pivot axes during pivotal movement of said lateral support arm means,

characterized in that the lateral support arm means includes teeth, by means of which they engage in aperture means provided in the support structure.

38. A support mechanism according to claim 37, wherein said support mechanism is a front support mechanism with said boot sole holding means including toe hold-down means, characterized in that the teeth are rounded-off approximately circularly shaped.

39. A ski boot support mechanism for safety ski bindings comprising:

a support structure attachable to a ski surface,
at least one boot sole holding means,
lateral support arm means attached to and movable
with each of said boot sole holding means,
pivot support means for supporting each of said lateral support arm means at said support structure
for pivotal movement about a support arm pivot axis which extends at least approximately perpendicular to said ski surface,
and resilient means for resiliently resisting pivotal movement of said lateral support arm means,
said pivot support means including roll-off means for accommodating predetermined movement of each of said support arm pivot axes during pivotal movement of said lateral support arm means,

characterized in that the lateral support arm means support themselves rolling-off at an outer wall of the support structure serving as roll-off means from the inside thereof.

40. A support mechanism according to claim 39, wherein said support mechanism is a front support mechanism with said boot sole holding means including toe hold-down means.

41. A ski boot support mechanism for safety ski bindings comprising:

a support structure attachable to a ski surface,
a pair of boot sole holding means,
a pair of lateral support arms attached one each to
and movable with respective ones of said boot sole holding means,
pivot support means for supporting each of said lateral support arms at said support structure for pivotal movement about respective support arm pivot axes which extend at least approximately perpendicular to said ski surface,
and resilient means for resiliently resisting pivotal movement of said lateral support arms,
wherein said resilient means includes spring means
having a central axis disposed intermediate to and substantially parallel with said supporting arm pivot axes, and wherein opposite end portions of the spring abut respective portions of the two lateral support arms.

42. A support mechanism according to claim 41, wherein said support mechanism is a front support mechanism with said boot sole holding means including toe hold-down means, characterized in that the spring means is a coil spring with the coil thereof surrounding said central axis.

43. A support mechanism according to claim 41, wherein said support mechanism is a front support mechanism with said boot sole holding means including toe hold-down means, characterized in that the ends of

the spring means are bent out in relation to the pivot axes of the respectively associated lateral support arm means in such a manner that with a lateral pivoting of the support arm means the spring means is at first additionally stressed and thereupon is again unstressed.

44. A support mechanism according to claim 41, wherein said support mechanism is a front support mechanism with said boot sole holding means including toe hold-down means, characterized in that the spring means is arranged on an adjustable pin adjustable in the ski longitudinal direction and disposed essentially perpendicularly to the ski surface.

45. A front support mechanism according to claim 44, characterized in that the axis of the pin carrying the spring means extends between the lateral support arm means and in that said pin is flattened off on both sides thereof between the lateral support arm means.

46. A front support mechanism according to claim 45, characterized in that the pin is flattened off on both sides between plate shaped members forming the support arm means.

47. A front support mechanism according to claim 44, characterized in that the pin is supported in a fork guided within slots of the support structure, said fork being longitudinally adjustably mounted.

48. A front support mechanism according to claim 47, characterized in that said fork is longitudinally adjustably arranged in an end wall of the support structure.

49. A front support mechanism according to claim 44, characterized in that the adjustable pin is constructed as indicating element for the spring tension.

50. A support mechanism in accordance with claim 41, wherein said spring means are arranged on an adjustable pin adjusted upon the ski longitudinal direction and disposed essentially perpendicularly to the ski surface.

51. A ski boot support mechanism for safety ski bindings comprising:

a support structure attachable to a ski surface,
a pair of boot sole holding means,
a pair of lateral support arms attached one each to and movable with respective ones of said boot sole holding means,
pivot support means for supporting each of said lateral support arms at said support structure for pivotal movement about respective support arm pivot axes which extend at least approximately perpendicular to said ski surface,
and resilient means for resiliently resisting pivotal movement of said lateral support arms, wherein said resilient means includes spring means having the ends thereof bent out in relation to the pivot axes of the respectively associated lateral support arms in such a manner that with a lateral pivoting of the support arms the spring means is at first additionally stressed and thereafter is again unstressed.

52. A ski boot supporting mechanism for safety ski bindings comprising:

a support structure attachable to a ski surface,
a pair of boot sole holding means,
a pair of lateral support arms attached one each to and movable with respective ones of said boot sole holding means,
pivot support means for supporting each of said lateral support arms at said support structure for piv-

tal movement about respective support arm pivot axes which extend at least approximately perpendicular to said ski surface, and resilient means for resiliently resisting pivotal movement of said lateral support arms, wherein said support means includes guide means for accommodating movement of the respective support arm pivot axes in a longitudinal direction along the respective support arm during pivoting of the respective support arm.

53. A support mechanism according to claim 52, wherein said pivot support means includes means for supporting said lateral support arms for pivotal movement independently of one another.

54. A support mechanism according to claim 52, wherein said support mechanism is a front support mechanism with said boot sole holding means including toe hold-down means.

55. A support mechanism according to claim 54, characterized in that said guide means includes roll-off means fixed at the support structure.

56. A front support mechanism according to claim 54, characterized in that the lateral support arm means are guided against lifting off from the roll-off means in roll-off contact with the lateral support arm means.

57. A front support mechanism according to claim 54, characterized in that pin means guided along arcuately shaped guide surface means are provided for the guidance of the lateral support arm means.

58. A front support mechanism according to claim 57, characterized in that said pin means are guided in arcuately shaped guide slot means.

59. A front support mechanism according to claim 58, characterized in that the guide surface means are arranged in the lateral support arm means and the pin means at the structural part.

60. A front support mechanism according to claim 58, characterized in that for purposes of guidance the pin means are arranged at the lateral support arm means and the guide surface means as inner walls at the support structure.

61. A front support mechanism according to claim 57, characterized in that the guide pin means are arranged in the center point of curvature of toothed means rolling-off at the support structure in the rest condition of the lateral support arm means.

62. A front support mechanism according to claim 54, characterized in that the roll-off movement of the lateral support arm means is limited by abutment means.

63. A front support mechanism according to claim 62, characterized in that the abutment means are arranged at the ends of the guide surface means.

64. A front support mechanism according to claim 63, characterized in that the abutment means are formed by transversely extending wall parts delimiting the guide surface means.

65. A front support mechanism according to claim 54, characterized in that in addition to the lateral support arm means, a central adjustable abutment means is provided for the support of the front portion of a ski boot.

66. A front support mechanism according to claim 54, wherein said guide means includes toothed means at said support structure, which toothed means are engageable with respective ones of said support arms during pivotal movement thereof,

67. A front support mechanism according to claim 66, characterized in that the toothed means include two teeth mutually offset in the ski longitudinal direction.

68. A front support mechanism according to claim 67, characterized in that the lateral support arm means include said teeth, by means of which they engage in aperture means provided in the support structure.

69. A front support mechanism according to claim 68, characterized in that the lateral support arm means support themselves rolling-off at an outer wall of the support structure serving as roll-off means from the inside thereof.

70. A front support mechanism according to claim 69, characterized in that the lateral support arm means are guided against lifting off from the roll-off means in roll-off contact with the lateral support arm means.

71. A front support mechanism according to claim 70, characterized in that for purposes of guidance the pin means are arranged at the lateral support arm means and the guide surface means as inner walls at the support structure.

72. A front support mechanism according to claim 71, characterized in that the guide pin means are arranged in the center point of curvature of the toothed means rolling-off at the support structure in the rest condition of the lateral support arm means.

73. A ski boot support mechanism for safety ski bindings comprising:

a support structure attachable to a ski surface, 30
at least one boot sole holding means,
lateral support arm means attached to and movable
with each of said boot sole holding means,
pivot support means for supporting each of said lateral support arm means at said support structure 35
for pivotal movement about a support arm pivot axis which extends at least approximately perpendicular to said ski surface,
and resilient means for resiliently resisting pivotal movement of said lateral support arm means, 40

said pivot support means including roll-off means for accommodating predetermined movement of each of said support arm pivot axes during pivotal movement of said lateral support arm means,

characterized in that the lateral support arm means project through apertures of the housing-shaped support structure and in that a threaded member arranged in a center web between the aperture means is provided as center adjustable abutment means for the front portion of the ski boot.

74. A ski boot support mechanism for safety ski bindings comprising:

a support structure attachable to a ski surface,
at least one boot sole holding means,
lateral support arm means attached to and movable
with each of said boot sole holding means,
pivot support means for supporting each of said lateral support arm means at said support structure for pivotal movement about a support arm pivot axis which extends at least approximately perpendicular to said ski surface,
and resilient means for resiliently resisting pivotal movement of said lateral support arm means,
said pivot support means including roll-off means for accommodating predetermined movement of each of said support arm pivot axes during pivotal movement of said lateral support arm means,
characterized in that the lateral support arm means include two plate-shaped members arranged one above the other at a distance which are connected with each other by at least one of the two parts consisting of wall means and guide pin means and which carry toothed means enabling the roll-off movement of the support arm means.

75. A support mechanism according to claim 74, wherein said support mechanism is a front support mechanism with said boot sole holding means including toe hold-down means.
